W. G. Charles
ATTORNEY.

Patented Apr. 12, 1927.

UNITED STATES PATENT OFFICE.

KARL C. PARKHURST, OF WICHITA, KANSAS.

TRAFFIC SIGNAL.

Application filed August 10, 1926. Serial No. 128,424.

My invention relates to traffic signals, and has for its chief object a signal that will collapse resting on the horizontal plane of the road bed.

5 A further object of my invention is to provide a signal that does not tend to overthrow a vehicle when contacting with the wheel thereof.

A still further object of my invention is 10 to provide a traffic signal that is plainly observed owing to its size and prominent position, the same being yieldable and not inclined to damage the tire of an automobile by sudden contact therewith.

15 A still further object of my invention is to provide a traffic signal that will reposition automatically when forced downward by a vehicle.

These and other objects will hereinafter 20 be more fully explained.

Referring to the drawings:

Fig. 1 is a perspective view of a collapsible type of my invention.

Fig. 2 is a transverse sectional view 25 through the signal plate.

Fig. 3 is a sectional view longitudinally taken on line 3—3 in Fig. 1 looking in the direction of the arrows.

The signal herein disclosed consists of a 30 mechanism that will collapse to the road level when in contact with the wheels of the vehicle, and when released will automatically rise to a visible position.

To accomplish such I have provided a bed 35 1 with a depression to form channels on each side thereof as shown at 2 in Figs. 2 and 3. The said plate having a curvature at both ends thereof as at A as means for the exclusion of sediment that will naturally collect 40 therein as hereinafter described.

In Fig. 1 is shown a pair of plates 3 which are hingedly connected as at 4' and being tensioned by springs 5 so that the said plates are inclined to fold together. On the visible 45 sides of the plates are placed such indicia words as may be required to control the traffic on highways. As to the style of the letters they may be constructed at the discretion of the manufacturer so long as they 50 are prominent in their appearance. Preferably they are to be made as a type of raised

letter having the face thereof polished, or may be colored. The plates are preferably made of metal to endure sudden contact.

The lower edges of the plate are adapted 55 to slide longitudinally in the bed with the dowels 6 engaging in the channels as means for proper alignment and to control the position thereof for service. As a convenient means for entering the plates in the channels of the bed I have provided a notch 7 on each side thereof through which the dowels will pass. When properly entered I have placed screws 8 threadedly engaging and extending across the channels functioning as 60 a stop for the dowels by which means the said plates are positioned at a desired angle, and at all times concentrically positioned 65 longitudinally in the bed.

Should the wheel contact the indicia plate 70 the opposite side will slide freely in the direction of the arrow B allowing the plates to collapse to a flush position with the plane of the bed channel as at C forcing any collection of sediment from the end of the bed 75 which can pass freely over the curvature thereof. Immediately after the wheel has passed over the said plates they will automatically erect themselves as shown in Fig. 1 being tensioned by the springs 5 as heretofore stated.

Such modifications may be employed as lie within the scope of the appended claims.

Having thus described my invention, what I claim as new and desire to secure by Letters Patent is:—

1. In a traffic signal, a bed imbedded in the surface of the road, a depression in the bed having channels on each side thereof, a pair of pivotally connected indicia plates having 90 dowels on the outer corners thereof to engage in said channels, springs engaging at the pivot point of the plates to cause said plates to move towards each other, stops engaging across said channels against which 95 said dowels will engage for an angled position of each of the plates.

2. In a traffic signal, a rectangular shaped bed having a depression in the plane thereof, curvatures at the opposite ends of the depression for sediment to pass freely from the 100 ends of said depression, a pair of hingedly

connected plates, indicia wording on the plane of the plates, springs tensioning the plates at the hinged connection, dowels on the opposite edges of the plates to engage in the channels of the bed so that said plates will press downward flush with the plane of the bed, a notch in the upper side of both

channels to enter said dowels to engagement in the channels, stops in the channels for said dowels to contact for an erect position of the plates as tensioned by said springs, all substantially as, and for the purpose described.

KARL C. PARKHURST.
